UNITED STATES PATENT OFFICE.

ARTHUR S. CAMPBELL, OF MANCHESTER, NEW HAMPSHIRE.

PALETTE-KNIFE AND BRUSH SUPPORTER.

SPECIFICATION forming part of Letters Patent No. 337,660, dated March 9, 1886.

Application filed January 15, 1886. Serial No. 188,619. (Model.)

To all whom it may concern:

Be it known I, ARTHUR S. CAMPBELL, of Manchester, in the county of Hillsborough and State of New Hampshire, have invented certain new and useful Improvements in Palette-Knife and Brush Supporters; and I do hereby declare the following to be a full, clear, and exact description of the invention, such as will enable others skilled in the art to which it appertains to make and use the same.

My invention relates to an improvement in palette-knife and brush supporters.

The object is to provide a support which may be readily and securely attached to paint or ink cans, and which will, when so attached, support a palette-knife and brush, one or both, in a position to drip into the can.

A further object is to provide a support which shall be neat in appearance, and which can be manufactured at a slight initial cost.

With these ends in view my invention consists in certain features of construction and combinations of parts, as will be hereinafter described, and pointed out in the claims.

In the accompanying drawings, Figure 1 is a view of the support in position for use, and Fig. 2 is a transverse section.

A represents a supporting-standard. It is provided with a longer leg, *a*, and a shorter leg, *a'*, which legs are separated by a narrow slot, *B*, adapted to receive the edge of a paint-can, *C*, as shown. The longer leg, *a*, is supposed, to rest in contact with the outside of the can, and the shorter leg, *a'*, with the inside of the can. To secure the standard in position on the can, a set-screw, *b*, is provided, which works in a threaded perforation, *C*, in the longer leg, and is adapted to impinge against the portion of the can located in the slot *B*.

In the upper end of the standard there is a narrow slit, *c*, formed, extending radially from the axis of the can, in which slit are secured the lower ends of a pair of spring-arms, *D*. The arms *D* gradually separate from each other as they extend upwardly, and form a rest for the blade of a palette-knife. The blade, when slightly pressed downwardly between the arms *D*, is clamped in position by their spring-pressure against its sides.

To support the handle of the knife, a bracket-like rest is formed, preferably of a single

piece of wire, *E*, one end of which is set firmly in the standard *A* near its upper end. From thence the wire extends outwardly in nearly a horizontal direction a distance of four inches, 55 more or less, to suit the sizes of knife and brush for which it is intended, where it is bent to form a pair of diverging loop-branches, *e*. It is then returned to the lower portion of the standard, making a half-twist around the horizontal portion and curving downwardly and inwardly to the point, where its end is firmly set in the standard. The handles, knife, and brush will rest securely between the said loop-branches *e*, while the blade of the knife and 65 the end of the handle to which the brush is attached will rest between the spring-arms *D*. The drippings from the end of the knife and brush are thus allowed to fall back into the can; the handles of the knife and brush are 70 kept from becoming soiled; a convenient place to lay the knife and brush, when not in use, is always at hand, and the rest may be removed from and applied to cans of various sizes and shapes without any appreciable waste of time. 75

It is evident that the shape and size of the spring-arms *D*, the wire-rest *E*, and the standard *A* might be changed, and that the wire-rest might be made in two or more pieces, instead of one, and of other material than wire, 80 without departing from the spirit and scope of my invention; hence I do not wish to limit myself strictly to the construction herein set forth; but,

Having fully described my invention, what 85 I claim as new, and desire to secure by Letters Patent, is—

1. In a palette-knife and brush support, the combination, with a standard adapted to be secured to the edge of a can or pot, of a handle-rest attached to the standard, substantially as set forth.

2. In a palette-knife and brush support, the combination, with a standard adapted to be removably secured to the side of a paint-receptacle, and provided with diverging arms for the reception of a knife-blade or brush, of a handle-support attached to the standard, substantially as set forth. 95

3. In a palette-knife and brush support, a 100 bifurcated standard adapted to embrace the edge of a can, and provided with a pair of

spring-arms set in its upper end, adapted to receive the knife or brush, or both, substantially as set forth.

4. In a palette-knife and brush supporter, the combination, with a bifurcated standard having a longer and a shorter leg, and provided with a pair of diverging spring-arms set in its upper end, and with a set-screw for locking it to a can, of a handle-support secured to the standard, substantially as set forth.

5. In a palette-knife and brush supporter, the combination, with a standard adapted to be removably secured to a paint-receptacle,

of a bent-wire bracket extending outwardly from the standard and provided with a pair ¹⁵ of branches adapted to receive the handle of a knife or brush between them, substantially as set forth.

In testimony whereof I have signed this specification in the presence of two subscribing witnesses.

ARTHUR S. CAMPBELL.
